DONALD B. FEGLES, OF MINNEAPOLIS, MINNESOTA

GRAIN-HANDLING APPARATUS

Application filed March 30, 1928. Serial No. 266,005.

This invention relates to new and useful improvements in grain handling apparatus, particularly adapted for use in grain elevators and terminal warehouses where uncleaned grain is received. Grain thus received is usually passed through a suitable grain separator and cleaner for the purpose of removing dockage therefrom. Frequently, when the foreign content or dockage contained in the grain is heavy, the desired result cannot be obtained in one cleaning operation, in which case, it is necessary that the grain be run through the cleaning machine a second time. In present installations, the grain separating and cleaning machines or units are usually mounted upon a floor in the building in such a manner that when the grain has been passed through one cleaning unit, and it is found that it still contains some dockage, it becomes necessary to elevate the grain back to the receiving hopper of the same unit for passage therethrough a second time; or, it may be elevated to the receiving hopper of another similar unit, positioned adjacent thereto.

To thus elevate the grain from the discharge of one unit to the receiving hopper of another, or to the same unit, requires suitable elevating mechanism which, obviously, adds to the cost of the installation and the cost of operation, and it also more or less complicates the apparatus and the handling of the grain or material and contributes to the degradation of the grain. It is therefore desirable that the installation of the apparatus be arranged in such a manner, that such operations as elevating the partially cleaned grain from the discharge of one cleaning unit, back to the receiving hopper of the same unit, or to the receiving hopper of an adjacent unit, be eliminated to simplify the handling of the grain and consequently the cost of such handling.

The object of the present invention is to arrange separating and cleaning units in such a manner that the grain may be delivered thereto from a common hopper, the connections between the hopper and the cleaning units being so arranged that all of the grain may be diverted from the hopper into a

selected cleaning unit, from which unit the grain, if not thoroughly cleaned, may be delivered to a second unit, arranged beneath the first unit, for further cleaning. Thus, the grain may be fed through two or more units arranged for series operation until the grain is ultimately cleaned to the desired degree. The connections between the common hopper and the cleaning units are also so arranged that the grain may simultaneously be delivered to two or more of the cleaning units from the hopper, thereby increasing the capacity of the apparatus because of such parallel operation of the grain cleaning units. 55 60 65

The particular object of the invention, therefore, is to provide an improved grain handling apparatus or method particularly adapted for use in grain elevators and terminal warehouses where grain is received from the producer for distribution, which comprises a plurality of grain cleaning units of like construction, arranged preferably one above the other and interconnected so as to increase the volume of the apparatus without increasing the horizontal distance required to spout the grain, and without increasing the ground area or space occupied by the grain cleaning units. The particular arrangement of the cleaning units is also such as to make possible the delivery of partially cleaned grain from one cleaning unit to another for repeat cleaning, without the necessity of re-elevating the grain; and the arrangement of the units further being such that the grain will feed by gravity from the discharge of one unit to the receiving hopper of another unit, thereby simplifying the apparatus and operation. 70 75 80 85

Other objects of the invention will appear from the following description and accompanying drawings and will be pointed out in the annexed claims. 90

In the accompanying drawings, there has been disclosed a structure designed to carry out the various objects of the invention, but it is to be understood that the invention is not confined to the exact features shown as various changes may be made within the scope of the claims which follow. 95

The drawing shows a diagrammatic view 100

illustrating the improved arrangement of the grain cleaning units and the means for feeding the grain thereto from a common hopper.

In the selected embodiment of the invention here shown, there is illustrated, for purposes of disclosure, a plurality of grain storage bins or garners 1, 2, 3, and 4 having spouts 5, 6, 7 and 8, respectively, leading therefrom to a common hopper 9. This hopper may be omitted if preferred. The grain discharge spouts 5, 6, 7, and 8 are each provided with a suitable slide or gate valve 11 whereby the delivery of the grain from the bins to the hopper 9 may be controlled.

An important feature of this invention resides in the novel arrangement of the grain separating and cleaning units 12 and 13, which, it will be noted, are preferably arranged in superimposed relation for conservation of space, but they may be in staggered relation upon different levels. These cleaning units, as they will hereinafter be referred to, are of conventional construction, and it is therefore thought unnecessary to show same in detail. The upper cleaning unit 12 has a receiving hopper 14 arranged directly beneath a feed spout 15 connected with a trunk 16 leading from the hopper 9. A suitable valve 17 is provided at the bottom 30 of the hopper 9 to control the delivery of grain to the cleaning units.

The lower cleaning unit is provided with a similar receiving hopper 18 having a spout 19 arranged thereover which communicates 35 with the trunk 16. Suitable valves 21 and 22 are provided in the spouts 15 and 19, respectively, to control the flow of grain therethrough. By thus connecting the receiving hoppers of the two cleaning units with the feed trunk 16, and because of the provision 40 of the valves 21 and 22, grain may be delivered from the hopper 9 to either one or the other of the two cleaning units, or, if desired, grain may be delivered to the two units 45 simultaneously from the hopper 9 so that the two cleaning units may be operated in parallel. By this expression I mean the grain may be passed through each unit without passing through the other.

The upper cleaning unit 12 has a grain discharge 23 from which a spout 24 leads to a suitable receiving means, not shown. The discharge 25 of the lower cleaning unit 13 similarly has a spout 26 which may be connected to the spout 24 so that grain discharging therefrom will be delivered into the same receiving means. Each cleaning unit is further connected with a dockage spout 27, as shown, through which the foreign content or dockage removed from the grain may be delivered to a suitable receiving means, not shown.

Frequently, grain received at a grain distribution point, such as an elevator, or terminal warehouse, must be passed through the

cleaning units two or more times before it is thoroughly cleaned to prepare it for shipment. This is conveniently brought about in the present invention because of the superimposed relation of the cleaning units. Referring to the drawing, it will be noted that the discharge 23 of the unit 12 has a spout 28 connecting it with the feed spout 19, leading from the feed trunk 16 to the receiving hopper 18 of the lower unit. A suitable valve 29 is provided at the junction between the spouts 24 and 28 so that grain discharging from the unit 12 may, if desired, be diverted into the receiving hopper of the lower unit 18, whereby the grain will again be cleaned as a result of its passage through the lower unit 13, from whence it will be delivered by the spout 26 to the spout 24, which discharges into the cleaned grain receiving means, not shown. When the grain is thus passed in series consecutively through the two cleaning units, the valve 22 will, of course, be closed and the valve 29 will similarly be closed to interrupt the delivery of grain from the discharge 23 of the unit 12 to the upper end of the spout 24. The cleaning units will thus be arranged for series operation, the grain being delivered into the upper unit from the feed trunk 16, then passed therethrough and is discharged into the spout 28 for delivery into the receiving hopper 18 of the lower unit 13.

From this unit, the clean grain flows into the spout 26 and into the lower end of the spout 24, while the dockage from both units is delivered into the dockage spout 27.

From the foregoing, therefore, it will readily be seen that by the particular arrangement and interconnecting of the cleaning units, they may readily be arranged for parallel operation, when it is found that the grain will be sufficiently cleaned by passing through only one unit, or, if it is found that the grain is not sufficiently cleaned, by passing it through one unit, the valves 21, 22, and 29 may be operated to cause the grain discharging from the hopper 9 to pass through the units successively. The particular arrangement and connections of the units therefore make it possible to operate the units either in parallel or in series, as may be desired, depending upon the condition of the grain.

In the drawing I have shown but two cleaning units, one arranged above the other. It is to be understood, of course, that I do not wish to be limited to this particular arrangement as, obviously, two or more units may be arranged in superimposed relation and also the units may be arranged in groups, two or more being placed upon the floor and each having one or more units arranged thereover, thus greatly increasing the capacity and efficiency of the installation, while at the same time requiring but minimum floor space.

The full lines 31 and 32 indicate floor locations. In an installation of the type set forth in this application, the cleaning units and the common hopper 9 are preferably arranged on floors below the bins or garners 1, 2, 3, and 4, which are arranged in the upper part of the structure.

I have shown in the drawing a plurality of bins, but I may substitute a single bin for 10 the group shown herein and instead of having the material delivered by gravity to the cleaning units, I may provide a suitable type of force feed, as for instance, a screw conveyor. Such a change, however, would be 15 merely the substitution of one well known feeding apparatus for another, and as the operation and result obtained would be substantially the same, I have not thought it necessary to illustrate these modifications. It 20 will be understood, also, that this apparatus will be incorporated in an elevator or warehouse with other mechanism pertaining to such a structure, all of which, having no immediate bearing on the invention herein described and claimed, is not illustrated or 25 described.

In various ways therefore, it will be understood the details of this apparatus or installation may be modified and still be within the 30 scope of my invention.

I claim as my invention:

1. A grain handling apparatus comprising in combination, a hopper; a plurality of bins having connections therewith, a plurality of 35 grain separating and cleaning units connected with said hopper, and means adapted to divert the grain from said hopper through said units for series operation, said means also being adapted to deliver grain from said 40 hopper to each of said units simultaneously for parallel operation.

2. A grain handling apparatus comprising in combination, a plurality of bins adapted to contain the grain to be treated, a plurality 45 of grain separating and cleaning units having pipe connections with said bins, and means whereby the grain may be directed to said units successively for operation in series or independently for separate or parallel operation.

3. A grain handling apparatus comprising a series of bins adapted to receive the grain to be separated, a hopper connected with said bins, a plurality of grain separating and 55 cleaning units having pipe connections with said hopper, and valves provided in said pipe connections for directing the grain successively through said units, or to either unit independently of the others.

60 4. A grain handling apparatus comprising in combination, a plurality of bins adapted to contain the grain to be handled, a plurality of grain separating and cleaning units arranged in superimposed relation, whereby an 65 economy of ground area may be effected, suit-

able pipes connecting said bins with said units, and means adapted to direct the grain through said pipes to said units in succession or for series separation or to either unit independently of the others for parallel separation.

5. A grain handling apparatus comprising in combination, a plurality of bins adapted to contain the grain to be treated, a plurality of grain separating and cleaning units arranged upon different levels and having pipe connections with said bins, each unit having a pipe connection with the other unit on an upper level and also having a suitable discharge, and suitable valves for said pipe connections adapted to divert the grain from said bins through each unit in succession or to each unit independently of the other unit.

6. A grain handling apparatus comprising in combination, a plurality of bins adapted to contain the grain to be treated, a plurality of grain separating and cleaning units arranged upon different levels and having pipe connections with said bins, each unit having a pipe connection with the other unit on an upper level and also having a suitable discharge, and suitable valves for said pipe connections whereby the grain from said bins may be directed through each unit in succession.

7. A grain handling apparatus comprising in combination, a bin, a plurality of grain separating and cleaning units and conveying connections between said bin and said cleaning units, said connections being adapted to direct the material to said units successively for operation in series or independently for separate or parallel operation.

8. A grain handling apparatus comprising a plurality of grain separating and cleaning units arranged at different levels, a system of conduits connecting said units, means whereby said units may be connected by said conduit system either in parallel or in series, and means for feeding grain to the upper end of said conduit system.

9. A grain handling apparatus comprising a plurality of grain separating and cleaning units, a system of conduits connecting said units, means whereby said units may be connected by said conduit system either in series or in parallel, and means for feeding the material to be cleaned to said conduit system.

10. A grain handling apparatus comprising a plurality of grain separating and cleaning units, means for feeding grain thereto, and means adapted to direct the material successively through said units for series operation, or simultaneously therewith for parallel operation.

In witness whereof, I have hereunto set my hand this 13th day of March 1928.

DONALD B. FEGLES. 130
